COLLAPSIBLE DISPLAY TRAY

Thomas H. Carruthers, Glendale, Ohio, assignor
to The McDonald Printing Company, Cincinnati,
Ohio, a corporation of Ohio

Application June 14, 1933, Serial No. 675,793

2 Claims. (Cl. 229—41)

My invention relates to collapsible display trays which may be shipped to a dealer in flat condition, and which he may open out and use as a display container by placing the articles to be displayed within an open topped container.

It is an object of my invention to provide a display carton having a flat bottom articulated to a side wall and in which the side walls are formed in a desirable shape, which the bottom wall fits into and in which means are provided to lock the bottom wall in position so that it will support the articles desired to be displayed.

Another object of my invention is the provision of a display tray of frusto polygonal pyramidal shape; in which the side walls are articulated together and the bottom wall is articulated to one of the side walls, and in which when the walls are assembled an open top container of frusto polygonal pyramidal shape is formed with the bottom wall firmly locked in position so that if the display tray is moved about there will be no likelihood of the bottom dropping out and permitting the contents to spill through the opening.

Another object of my invention is the provision of a display tray which can be cut from paper board stock with great economy and which can be assembled easily.

A further object of my invention is the provision of a display tray in which a bottom articulated to one of the side walls is provided with articulated flaps which extend up within the walls of the container when it is set up and so tend to make the package sift-proof at the bottom.

Another object is the provision of a display carton having overlapping flaps at the back, providing a reinforced structure which will support a display panel.

Specifically it is an object of my invention to provide a collapsible container or display tray in which a bottom wall, articulated to one of the side walls, has articulated flaps at the outer edge of the bottom which are provided with hook members which interlock within slots formed in one of the side walls so that the hook members will hold the bottom securely within the walls of the container.

It is further an object of my invention to provide a collapsible display tray in which the hook members seat naturally in the opening up of the tray without its being necessary to manipulate the hook members to seat within the slots.

In the Larkin Patent No. 1,860,349, there is disclosed a collapsible container of the general type forming the subject matter of this invention. In the collapsible container forming the subject

matter of the Larkin patent, there is a folding bottom comprising two sections connected to opposite sides, and centrally hinged to one another. Portions of the bottom at the extremities of the side line wedge into the adjacent dihedral angles of the pyramid to assist in holding the container expanded. It is my object to provide a container in which the folding bottom is formed from a flat unscored piece of polygonal shape, which is held in position not by any frictional engagement between the edges of the bottom with the side walls, but by the positive interlock of the tabs articulated to the bottom member. Thus, the possibility of the bottom pushing through the container and spilling the contents of the tray through the opening is minimized.

The above objects and other objects to which reference will be made in the ensuing description, I accomplish by that certain combination and arrangement of parts of which I have shown a preferred embodiment.

Referring to the drawings:

Figure 1 is a plan view of the cut and scored blank for forming the frusto polygonal pyramidal container.

Figure 2 is a plan view of the display tray in knocked down condition.

Figure 3 is a perspective view of the tray after it has been set up.

Figure 4 is a sectional view taken along the lines 4—4 in Figure 3.

Referring to the blank, the front side panel is indicated at 1, with other side wall panels 2 articulated to the side edges of the panel 1, and with other side panels 3 articulated to the outer edges of the panels 2. Panel 4 articulated to the left hand of the panel 3, shown at the left in Figure 1, forms the back wall of the box, and an articulated tab 5 connected to the outer edge of the panel 3, shown in Figure 1, overlaps the panel 4 and may be adhesively or by stitches secured thereto. A slot 6 is formed along the juncture between the line of articulation of the panel 3 and the panel 4, and a slot is formed in the side back wall opposite to the slot 6 by means of cut-out portions 7, 7a, which register and form a single slot of the same size as the slot 6. A bottom wall 8 is articulated to one side edge of the front panel 1. At each edge of the bottom 8 there is an articulated flap. As shown in Figure 1, two flaps 9 are provided at the front of the bottom. Two flaps 10 at the back of the bottom have hooked members 11 which interlock the bottom and hold it in place as will be later described.

50
55

The actual back end of the bottom is provided with flap 12.

When the flap 5 is brought with its line of articulation to the flap 3 in registry with the outer edge of the panel 4, the flaps 5 and 4 are secured together as by means of stitching 12 or an adhesive joint.

Referring to Figure 2, it will be observed that when the bottom 8 is bent upwardly so that it lies in alignment with the front panel 1, the panels 2 and 3 will overlie one the other and the joined panels 4 and 5 will lie against the bottom and also parallel with the front panel 1.

I have shown a display panel 13 secured to the back wall 4 with suitable stitching as indicated at 14. The panel 13 may be cut from the scrap from which the blanks shown in Figure 1 are cut, and the only cooperative action of the panel 13 aside from its mounting on the back panel 4, is that it has under-cut ledges 15, which as indicated in Figure 3, seat on top of the top edges of the panels 3 when the display tray is set up as indicated in Figure 3.

To set up the container from the flat collapsible condition shown in Figure 2, the corner edge between the flaps or panels 2, 3 are pushed together, which causes the side walls together with the front and back wall 1 and 4 to assume a polygonal formation. The bottom wall 1 carrying the side edge flaps 9, 10 and 12, are then pushed down within the polygonal side walls of the container. The flaps 10 fold inwardly into alignment with the panels 3 and as the bottom is depressed more and more the tongues 11 enter into the grooves 6, 7a, and when the neck of the tongues reaches the bottom of the groove, the bottom wall of the container will be held in secure position.

To collapse the container all that is necessary is to push upwardly on the back edge of the

bottom wall and the bottom 8, together with its flaps 10 and tongues 11 will move up out of the slots 6, 7a, thereby allowing the container to be collapsed into flat condition.

It will be noted that all of the container with the exception of the panel 13 is formed from a single sheet of paper board, and if the flap 12 were made longer it could itself be made sufficiently long to extend up as a display panel.

Having thus described my invention, what I claim as new and desire to secure by Letters Patent of the United States is:—

1. In a collapsible display tray comprising sides and a bottom member, said bottom member being articulated to the bottom edge of one of the sides, said sides being collapsed with said bottom member positioned within said sides and parallel to them, means for holding said bottom member in position within said sides when said tray is erected, said means comprising tab members projecting from the edge of said bottom member and slots in said side members to receive said tab members when said tray is erected, said slots being wedge shaped with the narrow portion of the wedge toward the bottom of the sides and appreciably wider than the tabs, so that the bottom member may be positioned within said side members and the tray erected by merely pushing said bottom member toward the bottom of the tray.

2. Means for holding the bottom of a collapsible display tray comprising sides and a bottom member consisting of tabs terminating in hooks articulated to said bottom member and projecting therefrom, and wedge shaped slots in said side members with the narrowest portion of the wedge toward the bottom edge for receiving said hooks when said bottom member is pushed into position in erecting said tray.

THOMAS H. CARRUTHERS.
